United States Patent Office.

BARTOLOMEUS J. OLEFF, OF MILWAUKEE, WISCONSIN.

Letters Patent No. 71,634, dated December 3, 1867.

IMPROVED SPRING-BED BOTTOM.

The Schedule referred to in these Letters Patent and making part of the same.

TO ALL WHOM IT MAY CONCERN:

Be it known that I, BARTOLOMEUS J. OLEFF, of the city and county of Milwaukee, and State of Wisconsin, have invented a new and useful Improvement in Spring-Bed Bottoms; and I do hereby declare that the following is a full, clear, and exact description thereof, which will enable those skilled in the art to make and use the same, reference being had to the accompanying drawing, forming part of this specification, in which—

Figure 1 is a plan view,

Figure 2 side view, and

Figure 3 an end view.

Similar letters of reference in each of the figures indicate corresponding parts.

The object of my invention is to produce a bed-bottom which shall be cheap in construction, and comfortable and easy to lie on.

A, the frame, the side pieces of which are straight, and the end pieces crowning; B, spiral springs; C, longitudinal slats; D, cross-slats woven into slats C, their ends fastened to the outside longitudinal slats; E, hooks connecting the longitudinal slats to one end of the frame A; F, hooks which connect the inner slats C in pairs to springs B. The two outer slats C are connected singly to their springs. The hook E of one of the outside longitudinal slats projects through the end piece of frame A, and has a nut, G, on it, with which to tighten the slat when its spring is stretched to require it. All of the hooks E may be made in this way, if desired, and thus afford means for tightening all the longitudinal slats. The spiral springs B are hooked into holes made for the purpose in the other end of the frame A.

This bed-bottom, as shown in fig. 1, with a mattress on it, forms a most complete sleeping-apparatus, the operation of which is obvious. It may be made of any material suitable for the purpose.

What I claim as my invention, and desire to secure by Letters Patent, is—

A bed-bottom made crowning, with slats C and D, springs B, and hooks E, in combination, substantially as and for the purpose described.

Also, hook E, with its nut G, in combination with the spring B and slat C, connected thereto for the purpose of tightening the slat and spring, as described.

Also, the arrangement of the inside longitudinal slats C in pairs, connected to springs B, with the two outside slats single, with their connections, as described.

BARTOLOM. JOS. OLEFF.
